ALBERT SCHMIDT, OF FLINT, MICHIGAN, ASSIGNOR TO CHAMPION IGNITION COMPANY, OF FLINT, MICHIGAN, A CORPORATION OF MICHIGAN.

SPARK-PLUG.

1,135,727.

Specification of Letters Patent. Patented Apr. 13, 1915.

Application filed May 29, 1914. Serial No. 841,744.

To all whom it may concern:

Be it known that I, ALBERT SCHMIDT, a citizen of the Republic of France, residing at Flint, in the county of Genesee and State of Michigan, have invented certain new and useful Improvements in Spark-Plugs, of which the following is a specification, reference being had therein to the accompanying drawings.

- 10 In the present state of the art in the manufacture of spark plugs, it is usual to incase the insulator member in a metallic bushing which is threaded for engagement with the engine cylinder. These elements are secured 15 together so as to form a gas-tight seal, but when the plug is in use in an engine cylinder and is subjected to the heat developed by the internal combustion, it frequently becomes leaky. This is due to the fact that the 20 coefficient of expansion of the metal is much greater than that of the porcelain or insulator, so that there is a loosening of the joint therebetween. It is one of the objects of the present invention to maintain a leak-proof 25 joint between the metal and the porcelain by initially forming said joint when the metal is heated to a temperature equal or in excess of any temperature to which it is subsequently subjected.
- 30 It is a further object to obtain a simple and expeditious method of forming the joint, and a simple and inexpensive construction of plug as hereinafter set forth.

In the drawings: Figure 1 is a longitudinal section through a spark plug showing the metallic bushing and insulator in engagement, but before the sealing joint is formed; Fig. 2 is a view illustrating the method of heating the metal and fashioning 40 the same to form the clamping joint; Fig. 3 is a similar view after the completion of the joint; and Fig. 4 is an elevation of the completed plug.

A is the metallic bushing provided with 45 the usual threaded nipple B, and which is formed with a main bore and a counter-bore with a shoulder C therebetween.

D is a comparatively thin annular flange at the upper end of the counter-bore.

50 E is the insulator which has an enlargement F for seating upon the shoulder C within the counter-bore of the plug.

To secure the insulator within the sleeve with a gas-proof seal, these parts are first

placed in engagement with gaskets G and H, 55 preferably formed of soft metal, such as copper, above and below the shoulder or enlargement of the porcelain. The metallic bushing is then engaged with the electrodes I and J of an electric welder, these electrodes being respectively arranged below and above the bushing. The electrode J is also in the form of a die, which engages the upwardly-projecting annular flange or fin D of the bushing. The current is then turned on and simultaneously an endwise pressure is applied to the electrodes. This will result, first, in heating the metal of bushing, the most intense heat being in the comparatively thin flange or fin D, but the body portion of the bushing being also heated to a comparatively high temperature. The pressure of the die J will then fashion the fin into a bead which is pressed against the gasket H, conforming exactly to the contour of said gasket and conforming the latter exactly to the contour of the insulator so as to produce a gas-tight seal. The plug thus formed will remain gas-proof regardless of the heat to which it is subjected in 80 use, for this heat can never equal that to which the metal was subjected when the sealing joint was formed.

Another advantage resulting from this method of forming the seal is that the metal 85 being in a plastic condition is free from resiliency and will more perfectly conform to the contour of the porcelain than is possible with the cold metal.

What I claim as my invention is:—

1. The method of uniting metallic bushings and insulators of spark plugs, comprising the placing of the insulator in the bushing, the heating of the metal of the bushing to a temperature equal to or in excess of 95 that to which it will be subsequently subjected in use, and the compression of the metal to form the sealing joint while thus heated.

2. The method of uniting the metallic 100 bushings and insulators of spark plugs, comprising the heating of the metal and the forcible fashioning of the same while hot into conformity to the insulator to form a gas-tight seal therewith.

3. The method of uniting metallic bushings and insulators of spark plugs, comprising the heating of the metal to a tempera-

ture at which it is plastic, and the application of pressure thereto to conform to the shape of the insulator and to form a sealing joint therewith.

- 5 4. The method of uniting metallic bushings and insulators of spark plugs, comprising the placing of the insulator in the bushing, placing a compressible gasket upon said insulator, heating the bushing to a temperature at which the metal is plastic, and compressing the metal while hot to conform the same to said gasket and the insulator.
- 10 5. The method of uniting metallic bushings and insulators of spark plugs, comprising the formation of the bushing with a thin flange, the engagement of the insulator with said bushing, the engagement of the bushing with an electric welder to heat the metal, and the application of pressure while the metal is hot to conform the thin flange to the contour of the insulator.

- 15 6. The method of uniting the metallic bushings with the insulators of spark plugs, comprising the placing of the insulator in initial engagement with the bushing, the engagement of the bushing between electrodes of an electric welder, one of said electrodes being of die form, and the application of pressure when the metal of the

bushing is hot to conform the same to the 30 contour of the insulator.

7. A spark plug, comprising an insulator and a metallic bushing forcibly conformed to said insulator and molecularly contracted thereupon to form a heat-resisting and gas- 35 proof seal.

8. A spark plug, comprising an insulator, and a hot-fashioned metallic bushing forcibly conformed to and contracted upon said insulator.

40 9. A spark plug, comprising an insulator, and a metallic bushing having an integral portion thereof hot-fashioned and forcibly contracted upon said insulator to form a sealing joint therewith.

45 10. A spark plug, comprising an insulator having an enlargement, and a metallic bushing provided with a shoulder on which said enlargement is seated and having an integral portion hot-fashioned and forcibly contracted upon said enlargement to form a sealing joint therewith.

In testimony whereof I affix my signature in presence of two witnesses.

ALBERT SCHMIDT.
